UNITED STATES PATENT OFFICE.

FRIEDRICH CARL BUNGE, OF BREMEN, GERMANY.

SHIP'S SIDE SCUTTLE.

Application filed September 21, 1928, Serial No. 307,501, and in Germany October 18, 1927.

Ships' side scuttles are known in which the window pane, by means of a metal frame surrounding it and of rocking pivots provided on this metal frame, is slidably and 5 rockably arranged in the window frame or window case connected with the ship's side. The rocking pivots are in this case guided in special slots in the window case, and the disadvantage has been found that the metal 10 frame is liable to jam with the window pane during the sliding of the latter, and a uniform packing of the window to provide a reliable exclusion of water is also difficult to attain.

15 These disadvantages are overcome by the present invention, a ship's side scuttle being provided in which the rocking pivots for the window pane are supported in slide pieces which are positively connected with one another.

20 The invention is illustrated by way of example in the accompanying drawings, wherein

Fig. 1 shows a view of the side scuttle according to the invention from the inside of the ship,

Fig. 2 a section on the line II—II in Fig. 1 on a considerably larger scale,

Fig. 3, on the right-hand side a partial 30 inside view of the side scuttle with the inside cover removed, and on the left a section of the line III—III in Fig. 2, on a scale somewhat larger than that of Fig. 1, and

Fig. 4 a cross-section through the side scuttle on the line IV—IV Fig. 3.

In Fig. 1, 1 denotes a window frame or window case connected with the ship's side, 2 the window pane itself, and 3 a metal frame or glass-holder surrounding and holding the window pane, while 4, 4 denote rocking pivots fitted to this metal frame.

According to the present invention the rocking pivots 4 are supported in slide pieces which are positively connected with one another, and in their sliding ensure a uniform 45 removal of the metal frame 3 from a packing 5 in the window case or a uniform pressing of this metal frame against the packing, an easy moving of the window for the opening 50 thereof, and a satisfactory fluid-tight packing when the side scuttle is closed.

In the constructional example illustrated there is provided for this purpose a slide piece 6, which is so arranged as to be slid- 55 able in a part 7 of the window frame or window case connected with the ship's side and

to be prevented from rotating. This slide piece 6 is arranged upon a screw spindle 8, which can be set in rotation by means of a crank capable of being fitted on to a square 60 stud 9 or other non-circular projection on the internal surface of the side scuttle. This screw spindle 8 is positively connected by any suitable means with a screw spindle 65 which moves a similar slide piece 6 supporting the other rocking pivot 4. In the constructional example illustrated this positive connection is established by a chain 10, which connects with one another corresponding chain wheels 11 upon the screw spindles 8 70 and is guided over guide rollers 12 and 13. This chain is lodged in a special casing 14 provided in the window frame 1, and buffer devices, such for example as springs 15, are provided on the inside wall of this casing, 75 which prevent the device from rattling by the chain striking against the wall of the casing in consequence of the vibrations of the ship. The casing 14 is closed by a cover 16 mounted on the internal surface of the 80 side scuttle, so that all the means of movement for the window pane are completely protected and inaccessible, and are so arranged as to facilitate lubrication. In the bottom of the casing member 7 supporting 85 the slide piece 6 is provided a groove 17.

From Fig. 2 it can be seen that the rocking pivots 4 are supported in the slide pieces with some clearance, as indicated at 18. This clearance may for example be produced by 90 making the length L of the bearing aperture in the slide piece for the reception of the rocking pivot 4 greater than the diameter of the rocking pivot 4, as shown in Fig. 4. By this play of the rocking pivots in the slide 95 pieces 6, slight irregularities which are produced in the casting of the comparatively large pieces of metal and also in the packing means can be compensated for without the supporting pivots being able to jam in the 100 slide pieces 6 and the movement of the window pane being impaired.

In Fig. 2 the inner limiting position of the slide piece 6 is indicated at 6', and at 3' the external outline of the metal frame 3 of 105 the window pane in the rocked condition, that is, in the open position of the window. From this drawing it is immediately obvious that the metal frame 3, by screwing back, can be pressed against the edge 19 of 110 the window frame 1, and thereby fixed in the open position, so that the open window can-

not be moved even by the vibrations of the ship or by wind, and even a rattling thereof in the open position cannot occur.

The device hereinbefore described is 5 equally suitable for ships' windows of elongated or of round form.

What I claim is:

1. A ship's side scuttle, consisting in combination of a frame for securing the side scuttle to the ship's side, a window frame carrying a pane of glass arranged in the interior of the first-mentioned frame, trunnions on opposite sides of the window frame, slide pieces 10 displaceably supported in the frame serving for securing the side scuttle to the ship's side, as bearings for supporting the trunnions of the window frame, a screw spindle acting on each of the slide pieces, supported in the frame serving for securing the side scuttle to the ship's side, means for positively connecting the two screw spindles with one another, a flange on the inner side of the frame for securing the side scuttle to the ship's side, a 15 cover, the two parts forming a casing for the reception of the means for positively connecting the two screw spindles with one another, and a special casing for each of the slide pieces extending from the flange on the inner side to the flange on the outer side of the frame for securing the side scuttle, as and for the purpose set forth.
2. A ship's side scuttle, consisting in combination of a frame for securing the side scuttle to the ship's side, a flange on the out- 20 25

side of this frame, a window frame carrying a pane of glass arranged in the interior of the first-mentioned frame, trunnions on opposite sides of the window frame, slide pieces 30 35 displaceably supported in the frame serving for securing the side scuttle to the ship's side, as bearings for supporting the trunnions of the window frame, a screw spindle acting on each of the slide pieces, supported in the frame serving for securing the side scuttle to the ship's side, means for positively connecting the two screw spindles with one another, a flange on the inner side of the frame for securing the side scuttle to the ship's side, a 40 45 cover, the two parts forming a casing for the reception of the means for positively connecting the two screw spindles with one another, and a special casing for each of the slide pieces extending from the flange on the inner side to the flange on the outer side of the frame for securing the side scuttle, as and for the purpose set forth.

In testimony whereof I have signed my name to this specification.

FRIEDRICH CARL BUNGE.
